UNITED STATES PATENT OFFICE

FRANK LO CASTRO, OF BROOKLYN, NEW YORK, ASSIGNOR TO ABRAHAM LEVY, DOING BUSINESS AS UNITED METAL GOODS MFG. CO., OF KINGS COUNTY, NEW YORK

DESIGN FOR A COMBINED LAMP AND CLOCK CASE

Application filed January 19, 1931. Serial No. 38,353. Term of patent 7 years.

To all whom it may concern:

Be it known that I, FRANK Lo CASTRO, a citizen of United States, residing at Brooklyn, in the county of Kings and State of New York, have invented a new, original, and ornamental Design for Combined Lamp and Clock Case, of which the following is a specification, reference being had to the accompanying drawing, forming part thereof.

Fig. 1 is a front view of a combined lamp and clockcase, showing my new design.

Fig. 2 is a side view thereof.

I claim:

The ornamental design for a combined lamp and clockcase, as shown.

FRANK LO CASTRO.
